UNITED STATES PATENT OFFICE.

KIRTLAND C. GARDNER, OF PITTSBURG, PENNSYLVANIA, ASSIGNOR OF ONE-HALF TO
UNITED ENGINEERING & FOUNDRY COMPANY, OF PITTSBURG, PENNSYLVANIA, A
CORPORATION OF PENNSYLVANIA.

METAL-TRANSFER APPARATUS.

No. 864,762.

Specification of Letters Patent.

Patented Aug. 27, 1907.

Application filed March 25, 1907. Serial No. 364,294.

To all whom it may concern:

Be it known that I, KIRTLAND C. GARDNER, of Pittsburgh, Allegheny county, Pennsylvania, have invented a new and useful Metal-Transfer Apparatus, of which the following is a full, clear, and exact description, reference being had to the accompanying drawings, forming part of this specification, in which—

Figure 1 is a partial plan view of a shear-table provided with my improved pusher mechanism, and Fig. 10 2 is a partial transverse section of the same.

My invention relates to transfer mechanism of the type wherein pushers force the metal sidewise on a table and are then released from the metal on the backward stroke. These pushers have ordinarily been 15 moved in an orbital path, moving upward after the forward push, thence back at the upper level, and thence down to the lower or pushing level. This involves a complicated mechanism, and such devices are also liable to injury by metal striking them as it is fed along 20 the table. My invention overcomes these difficulties, and it consists in providing the pusher head with depending loose links or bars which are arranged to swing forwardly on the retraction of the head, and also sidewise in case they are struck by another piece coming 25 upon the table or support.

In the drawings, 2 represent the rollers of a table, which in this case is a portion of a shear-table. These rollers may be driven or not, as desired; or the table or support may be without rollers.

30 3 is the pusher head, which is in the form of a cross-head resting on the guide 4, which is shown as overhanging the driving mechanism 5 for the table rollers. The cross-head is preferably arranged above the level of the upper surface of the metal fed upon the table; 35 and may be reciprocated by any suitable connections shown in the present form as comprising a rearwardly projecting rack 6, engaged by a pinion 7 on the shaft 8, which may be rotated through any suitable connections. The cross-head is provided with upwardly projecting horizontal bearings 9, supporting projecting stub-shafts 10 whose front ends are provided with ears 11, between which are pivoted the depending steel pusher bars 12. These pusher bars extend down below the level of the lower face of the cross head and into 45 the path of the metal. The cross-head prevents them from swinging backwardly; and as the cross-head moves forwardly they will push the metal, indicated at 13, forwardly on the rollers 2. If desired the metal may be pushed off the side of the table, the pusher bars having 50 preferably a range of movement between the dotted

and full lined positions *a* and *a'* shown in Fig. 2. On the return stroke of the head, the pusher bars will swing forwardly until they pass the metal, when they will drop down into operative position. If at any time an entering section of metal should strike the side face of any of 55 the pusher bars, they will simply swing sidewise idly and thus avoid injury to the apparatus.

The advantages of my invention result from the use of the pivoted pusher bars which are arranged to swing substantially at right angles to their plane of movement; and also forwardly during retraction. This avoids the use of complicated mechanism, and also prevents injury to the pusher by the metal striking it while moving on the table.

Many changes may be made in the arrangement of 65 the table or supports; the pusher head; the connections, and the mounting of the pusher bars to allow their swinging in planes at an angle to each other, without departing from my invention.

I claim:—

1. In a metal transfer mechanism, a pusher head, a pusher pin pivoted thereon and arranged to swing in different planes, said planes being at an angle to each other, and a stop device arranged to prevent back movement of the pin in one direction; substantially as described. 75
2. In metal transfer apparatus, a table or support, a reciprocating head arranged to move across and over the table, pusher bars pivoted to the head and arranged to swing in different planes, said planes being at an angle to each other, and a stop device arranged to prevent the bars 80 swinging backwardly in one direction; substantially as described.
3. In metal transfer apparatus, a pusher head having a depending swinging pusher bar mounted to swing sidewise as well as forwardly, the head being arranged to 85 prevent backward swinging of the bars; substantially as described.
4. In metal transfer apparatus, a table or support, a horizontal reciprocating head supported at one side thereof and movable across and over the table, and a swinging pusher bar pivoted to the upper part of the head and depending below the level of the head, said head forming a stop to prevent rearward swinging of the pusher bar; substantially as described. 0
5. A metal transfer apparatus, a table or support, a support at one side thereof, a reciprocating head on the latter support arranged to move across and over the table, and a depending pusher bar pivoted to a rock shaft mounted on the reciprocating head and arranged to swing in a plane at an angle to the plane of movement of the head; 100 substantially as described. 95

In testimony whereof, I have hereunto set my hand.

KIRTLAND C. GARDNER.
